CHAIN PROPULSION FOR BOATS
Herbert F. Bucklew, Vallejo, Calif.
(4610 Junction, Detroit 10, Mich.)
Filed Apr. 1, 1960, Ser. No. 19,256
3 Claims. (Cl. 115—63)

This invention relates to a novel and improved boat having chain propulsion.

The primary object of the invention is to provide a more efficient and stable boat of the kind indicated, which involves chain propellers along the sides of its hull which work through open-bottom channels or tunnels formed in the hull, inwardly of the sides of the hull, the channels having open rear ends opening through the stern of the hull.

Another object of the invention is the provision of a boat of the character indicated above, capable of operation at high and low speeds, wherein the paddles on the lower or working flights of the propulsion chains are engaged in the water beneath the bottom of the hull, and outer stabilizing fins extend downwardly from the bottom at and along the outer sides of the working flights, and are supplemented by a center fin or keel on the boat bottom.

A further object of the invention is to provide, in a boat of the character indicated above, more efficient, practical, and mechanically advanced propulsion chains, wherein links and paddles are readily replaced when necessary.

Other important objects and advantageous features of the invention will be apparent from the following description and the accompanying drawings, wherein, for purposes of illustration only, a specific form of the invention is set forth in detail.

In the drawings:

FIGURE 1 is a contracted bottom plan view of a boat of the present invention;

FIGURE 2 is a vertical longitudinal section taken on the line 2—2 of FIGURE 1;

FIGURE 3 is an enlarged vertical transverse section taken on the line 3—3 of FIGURE 2; and,

FIGURE 4 is a further enlarged fragmentary exploded perspective view showing propulsion chain structure.

Referring in detail to the drawings, wherein like numerals designate like parts throughout the several views, the illustrated boat comprises a hull 10 having a flat bottom wall 12 having a preferably full-length centered keel fin 14 on the bottom wall, side walls 16 which preferably cant outwardly and upwardly, a forward inclined prow 18, and a flat straight stern 20.

Extending for a substantial portion of the length of the hull 10, forwardly from the stern wall 20, is a propulsion assembly 22, which involves two similar chain tunnels 24 which are located close to but are spaced laterally inward from related hull side walls 16, open through the hull bottom wall 12, as indicated at 25, at and close to the inward sides of side fins 26 which extend downwardly from the hull bottom wall 12, and are spaced somewhat laterally inwardly from the hull side walls, as shown in FIGURE 3. The channels 24 open, at full height, through the hull stern wall, as indicated at 28. The tops of the channels 24 are closed by flat top walls 30 extending along the upper edges of the outward and inward channel sidewalls 32 and 34, respectively. A deck 36 can extend across the hull 10 between the hull sides and have portions which constitute the channel top walls 30. Arcuate front end walls 38, which can be continuations of the top walls 30 and curve downwardly and rearwardly therefrom, extend between the channel sidewalls 32, 34, and terminate at their lower ends, on a level with and joined to the hull bottom wall 12, as shown in FIGURE 2.

2

Extending between the channels 24 and journaled through their sidewalls, near the forward ends of the channels, is a transverse horizontal drive shaft 40, which is journaled at its ends in bearings 42 mounted on the outer sides of the outer channel sidewalls 32, thrust collars 44 and 46 on the shaft being engaged with the facing sides of the channel sidewalls. A similar rear idler shaft 48 is similarly mounted on the channels 24, close to and within the open rear ends of the channels.

Circumposed on and suitably fixed on the shafts 40 and 48, within the channels 24 and between the thrust collars 44 and 46, are forward and rear flat cylindrical sprocket drums 50 and 52, respectively, which occupy major portions of the width of the channels 24, having flat circular rims 54 on which are fixed centered, circumferentially spaced sprocket teeth 56. Sprocket propulsion chains 58 are trained around the forward and rear drums on the sprocket teeth.

The propulsion chains, as shown in FIGURE 4, preferably comprise pairs of elongated flat link plates 60, having removable bolts 62 extending through openings 64 in their ends, and intervening link blocks 66, which space the link plates 60 and extend between adjacent pairs of link plates, at their ends, the link blocks, at their ends, being journaled on related bolts 62. At equally spaced intervals along the sprocket chains 58, paddle assemblies 68 are mounted, which comprise elongated channel-shaped plates 70, which are long enough to subtend several links of the chains 58, and have flat webs 72 and parallel side flanges 74. Bolts 76 extend between the side flanges 74, at the middle thereof, through holes 77, and take the places of chain link bolts 62, and serve to mount the paddle assemblies 68 on the outer sides of the chains 58, so as to pivot and tilt, relative to the chains, as shown in FIGURE 2, as the chains go around the sprocket drums.

It is to be noted that the channel-shaped plates 70 closely fit on the chains 58 and that their side flanges 74 do not project substantially, at their free edges 76, inwardly beyond the inner sides of the chains 58.

As also shown in FIGURE 2, the upper and lower flights 78 and 80, respectively, of the chains 58, slide supportably along and against the upper and lower horizontal walls 82 and 84, respectively, of hollow, longitudinally elongated chain supports 86, which extend between the channel side walls 32, 34 and are fixed thereto, and which reach longitudinally between the forward and rear sprocket drums 50, 52. The chain supports 86 have concave end walls 88 and 90, which are close to and are concentric with the sprocket drums 50 and 52, respectively. The lower walls 84 of the chain supports 86 are located substantially in the plane of the hull bottom wall 12.

The paddle assemblies 68 further comprise single, longitudinally centered outstanding rectangular paddle plates 92, which are wider than the channel plates 70 and are suitably fixed thereto, and extend at right angles thereto, as shown in FIGURE 4, and have brace blocks 94, at opposite sides thereto, which extend to the webs 72 of the channel plates 70, on which the paddle plates are suitably rigidly fixed. As shown in FIGURES 2 and 3, the paddle plates 92 have free outer edges 96 which are close to but do not reach below the preferably rounded lower edges 98 of the side fins 26 on the hull bottom 12.

For driving the drive shaft 40 and the forward driven sprocket drums 50, a suitable motor 100 is mounted, as on a platform 102, at the forward ends of the channels 24, and has a short rearwardly extending shaft 104, having a bevel pinion 106 thereon, which is in mesh with a bevel ring gear 108 fixed on the inward side of a driven sprocket drum 50. Operation of the motor 100 in one direction runs the lower flights 80 of the propulsion chains 58 rearwardly along the open lower ends of the channels 24, so that water is pushed rearwardly along lower parts of

the channels 24, and the paddle plates 92 grip the water and supplement the rearwardly moving water in the channels 24, for driving the boat forwardly in the water. Reversing the forward travel of the boat is done by reversing the direction of travel of the propulsion chains 58. For steering the hull 10, a preferably suspended rudder 110 is provided, which is hinged high on the hull stern 20, above the channels 24. Steering of the hull 10 can also be accomplished by running one propulsion chain 58, while stopping the other propulsion chain, or by running the propulsion chains in opposite directions.

It is to be observed that the presence of the side bottom fins 26, and the keel fin 14, and the location of the lower flights of the propulsion chains 58 and their paddle plates 92 immediately at the inward sides of the side fins 26, produces a broad, rearwardly travelling stream of water, beneath the hull bottom 12, between the side fins 26 and the keel fin 14, which is confined by the side fins, and that, besides aiding propulsion of the boat, stabilizes the hull 10 in the water, against undue tipping, and against sliding sidewise, when operated at high and low speeds.

A lifting plane or water-foil 112, spaced downwardly from the hull bottom 12, can be provided, which is connected to and extends between the side fins 26 and the keel fin 14, at a location spaced forwardly from the channels 24, and near the prow 18 of the hull, for resisting tendency of the boat to nose-down forwardly in the water, when travelling at high forward speeds.

While there has been shown and described herein a preferred form of the invention, it is to be understood that the invention is not necessarily confined thereto, and that any change or changes in the structure of and in the relative arrangements of components thereof are contemplated as being within the scope of the invention as defined by the claims appended hereto.

What is claimed is:

1. A boat comprising a hull having a flat bottom wall, upstanding side walls, a prow, and an upright stern wall, said hull bottom wall having depending longitudinal side fins thereon and located close to said hull side walls, a central keel fin depending from said bottom wall and equally spaced from the side fins, said hull having longitudinal channels therein located along and spaced inwardly from the hull side walls, said channels having rear ends opening full height through the hull stern wall and open bottoms opening through the hull bottom wall, immediately at the inward sides of the side fins, said channels extending forwardly from the hull stern wall and terminating in longitudinally spaced relation to the hull prow, forward end walls closing the forward ends of the channels, and endless propulsion assemblies located within and extending along the channels, said assemblies comprising flexible belts having upper and lower flights having paddles thereon, the lower flights being located at the open bottoms of the channels with the paddles of the lower flights extending downwardly therefrom and downwardly from the hull bottom wall close to the inward sides of the side fins, said chains comprising spaced side links, link blocks having ends disposed between related ends of adjacent side links, bolts journalled through related ends of side links and link blocks, said paddle comprising longitudinally elongated channel plates having webs and side flanges, said channel plates being engaged over outward sides of the chains and subtendig several intermediate their ends and serving as pivots for the channel plates.

5 2. A boat comprising a hull having a flat bottom wall, upstanding side walls, a prow, and an upright stern wall, said hull bottom wall having depending longitudinal side fins thereon and located close to said hull side walls, a central keel fin depending from said bottom wall and

equally spaced from the side fins, said hull having longitudinal channels therein located along and spaced inwardly from the hull side walls, said channels having rear ends opening full height through the hull stern wall and open bottoms opening through the hull bottom wall, immediately at the inward sides of the side fins, said channels extending forwardly from the hull stern wall and terminating in longitudinally spaced relation to the hull prow, forward end walls closing the forward ends of the channels, and endless propulsion assemblies located within and extending along the channels, said assemblies comprising flexible belts having upper and lower flights having paddles thereon, the lower flights being located at the open bottoms of the channels with the paddles of the lower flights extending downwardly therefrom and downwardly from the hull bottom wall close to the inward sides of the side fins, said chains comprising spaced side links, link blocks having ends disposed between related ends of adjacent side links, bolts journalled through related ends of side links and link blocks, said paddle comprising longitudinally elongated channel plates having webs and side flanges, said channel plates being engaged over outward sides of the chains and subtendig several intermediate their ends and serving as pivots for the channel plates, the channel plate webs having paddle plates having inward ends fixed to the webs and free outer ends, the paddle plates being located intermediate the ends of the channel plates and disposed at right angles thereto.

3. In a boat hull having a downwardly opening longitudinal channel opening to the stern of the hull, an endless propulsion chain disposed longitudinally in said channel, said chain having alternating link blocks and links pivoted together, longitudinally spaced channel plates embracing one side of adjacent blocks and links, said channel plates having webs bearing upon the said one side of links and blocks and side flanges bearing against related sides of links and blocks, pivots traversing the side flanges, at a point intermediate their ends, and mounting the channel plates on the chain, paddle plates fixed to and extending laterally outwardly from the webs of the channel plates, and rotary drums mounted across said channel around which the chain is engaged at opposite ends thereof.
